UNITED STATES PATENT OFFICE.

RICHARD W. JEFFERIS, OF CAMDEN, NEW JERSEY, ASSIGNOR TO MERRITT & COMPANY, A CORPORATION OF PENNSYLVANIA.

PANEL FOR METAL LOCKERS.

No. 810,948.

Specification of Letters Patent.

Patented Jan. 30, 1906.

Application filed April 29, 1904. Serial No. 205,483.

To all whom it may concern:

Be it known that I, RICHARD W. JEFFERIS, of Camden, county of Camden, and State of New Jersey, have invented an Improvement 5 in Panels for Metal Lockers, of which the following is a specification.

My invention relates to the construction of panels for metal lockers, and may be used for the side panels, doors, base-frames, or other 10 parts of the locker.

The panel usually consists of an outer face, to which is secured a sheet of ordinary sheet metal having one or more openings in its body, over which reticulated metal is arranged and secured at the edges. A part of my 15 improvements relate to the means for securing the sheet metal and the reticulated metal firmly together without the use of rivets, whereby a very neat, light, and strong panel 20 is obtained. While an outer metal frame is usually employed to give greater strength and rigidity, it is not essential, and in some cases, particularly in doors, it may be omitted, the outer edges being strengthened by bending 25 the sheet metal upon itself.

In the accompanying drawings, Figure 1 is a front elevation of a set of two metal lockers embodying my invention, the door of one locker being removed. Fig. 2 is a side elevation 30 of the locker. Fig. 3 is a longitudinal vertical sectional view on the line A A of Fig. 1. Fig. 4 is a horizontal sectional view on the line B B of Fig. 1, enlarged; and Fig. 5 is a transverse section of one of the panels, enlarged.

The locker is composed of side panels *a*, a base-piece *b*, top *c*, back *d*, and door *e*. The side panels, base, and door are preferably formed with an outer frame of angle-irons *m*. The top is usually formed of sheet metal and the back of reticulated or plain sheet metal.

The present invention relates particularly to the construction of the surface of the panels, &c., and while I have shown this construction combined with outer metal frames *m*, formed of angle-irons, I do not mean to limit myself thereto, as the particular construction or use of the outer frame is not material to my invention.

A sheet of ordinary sheet metal *f* is secured at its outer edges to the angle-irons or metal frames, either by bending it over the flanges or by riveting it, if desired. One or more large openings *g* are cut in this metal

sheet, and the edges *n* about the openings are 55 bent back. A sheet of expanded metal or worm-wire *h*, cut to a size slightly larger than the opening in the sheet *f*, is laid over the opening with its outer edges resting on the bent edges *n*, which are then bent back, as at 60 *i*, over the edges of the expanded metal to inclose them and secure the expanded metal sheet in place. The inclosing bends are compressed to grip the edge of the expanded metal tightly, and the extremities of the 65 bends of the sheet metal are bent in, as at *j*, to form a rounded edge. When the opening in the sheet metal is formed with rounded corners *k*, as shown, the bent edges may be split or divided at those points, as indicated 70 in dotted lines in Fig. 4, to produce the curved effect, or the metal at the corner bends may be cut off.

The panel thus formed consists of an outer border of closed sheet metal and one or more 75 inner portions of reticulated metal carried thereby. This construction may be used for any part of the locker. In Figs. 1 and 4 it is shown applied to the door, and in Figs. 2 and 4 to the side panels. In these, because of the 80 greater vertical length, two openings provided with expanded metal are employed.

In Fig. 4 the construction is shown applied to the base-frame, and here a single opening is employed. It is also shown applied to the 85 back in this figure. The backs will, however, usually be made of plain sheet metal or of reticulated metal.

The bent edges of the sheet metal are clamped tightly upon the edges of the expanded metal or woven wire, so that no rivets or other fastenings are required, and bending of the edges of the reticulated metal, which is impractical in the case of stiff expanded metal or heavy woven wire suitable 95 for lockers, is not necessary.

The construction is not only light and strong, but very neat and effective in appearance.

What I claim as new, and desire to secure 100 by Letters Patent, is as follows:

1. A metal panel for lockers and the like, consisting of an outer metal frame composed of angle-irons and a wall carried by said frame and formed partly of closed sheet metal 105 and partly of reticulated metal, the closed portion of said wall consisting of a continuous sheet of metal secured at its outer edges

to the angle-irons and having an opening bounded by a continuous portion of sheet metal of substantial width, the edges of the sheet metal about said opening being bent 5 back upon the body of the sheet, and the reticulated portion consisting of a sheet of reticulated metal arranged over said opening with its edges resting on the backwardly-bent edges of the closed sheet metal, said bent 10 edges being again bent forward over the edges of the reticulated metal and inclosing them.

2. A metal panel for lockers and the like, consisting of an outer metal frame composed 15 of angle-irons and a wall carried by said frame and formed partly of closed sheet metal and partly of reticulated metal, the closed portion of said wall consisting of a continuous sheet of metal secured at its outer edges

to the angle-irons and having an opening bounded by a continuous portion of sheet metal of substantial width, the edges of the sheet metal about said opening being bent back upon the body of the sheet, and the reticulated portion consisting of a sheet of reticulated metal arranged over said opening with its edges resting on the backwardly-bent edges of the closed sheet metal, said bent edges being again bent forward over the edges of the reticulated metal and inclosing them and the extremities of said bent edges being bent in as at γ to form a rounded edge.

In testimony of which invention I hereunto set my hand.

RICHARD W. JEFFERIS.
